SETTING TOOL

Erwin Burns, Los Angeles, and Harry P. Wicker-sham, Huntington Park, Calif.

Application November 6, 1935, Serial No. 48,514

12 Claims. (Cl. 166—10)

This invention relates to a well tool and relates more particularly to a setting tool for facilitating the arranging or setting of liners and other equipment in wells. A general object of 5 this invention is to provide a simple, practical and dependable setting tool.

Liners are usually run into the producing portions of wells on strings of pipe and are set or suspended to line the open parts of the wells and 10 conduct the flowing well fluids into the casing or tubing. Devices known as setting tools are employed to facilitate the setting and removal of liners and the like. A setting tool is operable to connect a liner or liner hanger with the lower 15 end of a string of pipe employed to run the liner into the well and following the setting of the liner or the liner hanger the setting tool is released to disconnect the string of pipe from the liner or liner hanger whereupon the string may be withdrawn 20 from the well leaving the liner in position in the well.

Another object of this invention is to provide a setting tool that forms a positive dependable connection between a liner, liner hanger or the like, 25 and a string of pipe employed to run the liner or liner hanger into the well, whereby the liner may be run into the well without danger of disconnection from the string.

Another object of this invention is to provide 30 a setting tool that is operable to transmit both right-hand and left-hand turning forces between the setting string and the liner hanger for the actuation or release of the liner hanger.

Another object of this invention is to provide 35 a setting tool of the character mentioned that is sturdy and capable of withstanding hard usage and of transmitting comparatively heavy rotational and longitudinal strains.

Another object of the invention is to provide a 40 setting tool that may be easily and quickly released when in the well. The setting tool of the present invention may be readily released when in the well by merely lowering the string slightly and then giving the string a partial rotation 45 whereupon the string may be pulled from the well leaving the liner and the outer part or adapter of the setting tool on the liner in the well.

A further object of this invention is to provide 50 a setting tool of the character mentioned in which the mandrel on the lower end of a string of pipe may be easily engaged and locked in the adapter on a liner or liner hanger in the well to provide for the removal of the liner from the well.

55 The various objects and features of our inven-

tion will be fully understood from the following detailed description of typical forms and applications of our invention, throughout which description reference is made to the accompanying drawings, in which:

Fig. 1 is a side elevation of one form of the setting tool provided by this invention showing it connecting the lower end of a string with a liner or a liner hanger and illustrating the principal parts of the tool in central vertical cross section. 10 Fig. 2 is an enlarged side elevation of the tool shown in Fig. 1 in a partially released condition illustrating the principal parts in central vertical cross section. Figs. 3 and 4 are enlarged transverse detailed sectional views taken as indicated by lines 3—3 and 4—4 respectively on Figure 1 illustrating the principal parts in central vertical cross section. Fig. 5 is a transverse detailed sectional view taken as indicated by line 5—5 on Fig. 2. Fig. 6 is an enlarged side elevation of the lock ring removed from the tool. Fig. 7 is an enlarged side elevation of the mandrel. Fig. 8 is a side elevation of another form of the invention with the parts in the locked position and illustrating the adapter and the lock ring in longitudinal cross section. Fig. 9 is an enlarged side elevation of the tool illustrated in Fig. 8 with the parts in the partially released positions showing the adapter and the lock ring in vertical cross section. Fig. 10 is a transverse detailed sectional view taken as indicated by line 10—10 on Fig. 8. Fig. 11 is an enlarged transverse detailed sectional view taken as indicated by line 11—11 on Fig. 8. Figs. 12 and 13 are transverse detailed sectional views taken as indicated by lines 12—12 and 13—13 on Fig. 9. Fig. 14 is a side elevation of the lock ring of the tool shown in Fig. 8 and Fig. 15 is a side elevation of the mandrel of the tool illustrated in Fig. 8.

The setting tool of the present invention includes, generally, an outer part or adapter 10, an inner part or mandrel 11 adapted to fit in the adapter 10 and a spring urged lock ring 12 on the mandrel 11 for cooperating with the adapter 10.

The adapter 10 is a tubular member adapted to be threaded or otherwise attached to a liner, a liner hanger or other device to be set or positioned in a well. In the particular application of the invention illustrated in the drawings the adapter 50 10 is threaded on the upper end part of a tubular member 13 which may be considered a liner or a liner hanger. The longitudinal opening 14 of the tubular adapter 10 is preferably as large in diameter as the opening of the member 13. The 55

upper end 15 of the adapter 10 is preferably inclined downwardly and inwardly to guide the mandrel 11 into the adapter opening 14. The adapter 10 is internally relieved or provided with 5 an internal annular groove 16. The groove 16 is spaced between the opposite ends of the opening 14 and preferably has flat horizontal upper and lower walls. A plurality of circumferentially spaced longitudinal grooves 17 is provided 10 in the wall of the opening 14. The longitudinal grooves 17 extend downwardly from the upper end of the adapter 10 to the annular circumferential groove 16. In the typical embodiment of the invention illustrated in the drawings there are 15 four equally spaced grooves 17 having vertical parallel side walls. The adapter 10 just described is intended to be connected to a liner, a liner hanger or other part to be set in a well, and is intended to remain on the liner, liner hanger 20 or part when the mandrel 11 is removed and the setting string of pipe is withdrawn from the well.

The mandrel 11 which constitutes the inner part of the setting tool is intended to be received in the longitudinal opening 14 of the adapter 10 25 and may be locked therein in a manner that permits its removal when in the well. The mandrel 11 is an elongate part which may be cylindrical in its general configuration. The mandrel 11 is provided at its upper end with means for facilitating its connection with the string of pipe or tubing employed to set the liner or other device in the well. In the typical case illustrated a sub 30 18 is threaded on a reduced upper end portion 19 of the mandrel 11. The lower end of the sub 18 forms a downwardly facing annular shoulder 20 on the mandrel. The typical sub 18 has a tapered screw threaded socket 21 in its upper end to receive a threaded pin 22 of a tool joint section or the like on the lower end of the string of 35 pipe for carrying and setting the liner. The lower portion 11^a of the mandrel 11 is enlarged in diameter to fit or extend into the opening 14 of the adapter 10 with suitable slight clearance. The upper end of the enlarged mandrel portion 11^a 40 forms an upwardly facing annular shoulder 23. In accordance with the invention the mandrel 11 is provided with spaced longitudinal grooves 24. In the construction illustrated there are two diametrically opposite longitudinal grooves 24 which 45 extend upwardly from the shoulder 23 to the reduced threaded pin portion 19. The grooves 24 are preferably straight and vertical. Circumferentially extending grooves or lateral branch grooves 25 join the longitudinal grooves 24. The 50 branch grooves 25 are spaced above the shoulder 23 and preferably extend rearwardly or in a counter-clockwise direction from the grooves 24. The branch grooves 25 are straight and provided with horizontal upper and lower walls. 55

60 The inner part or mandrel 11 of the setting tool has projecting parts or elements for engaging in the adapter 10. Circumferentially spaced lugs 26 are provided on the lower or enlarged portion 11^a of the mandrel 11. There are four equally 65 spaced lugs 26 for cooperating with the four circumferentially spaced longitudinal grooves 17 in the adapter 10. The lugs 26 may be rectangular having flat vertical sides and flat horizontal ends. The lugs 26 of the mandrel 11 are 70 portioned to readily move or pass through the longitudinal grooves 17 in the adapter 10. In accordance with the invention the lugs 26 are adapted to enter the annular groove 16 of the adapter 10 and are adapted to have substantial vertical 75 play or movement in the groove 16. The extreme

lower end of the mandrel 11 has a downwardly and inwardly inclined surface 27 which assists in guiding or directing the mandrel into the tubular adapter 10. The mandrel 11 is provided with a central longitudinal fluid passage 28 which 5 communicates with the opening in the setting string to conduct fluid to the adapter 14 and the liner or liner hanger to flush out the liner.

The lock ring 12 surrounds the mandrel 11 and is shiftable or slideable on the mandrel. The lock ring 12 is arranged on the mandrel 11 between the shoulder 20 and the shoulder 23 and normally bears downwardly against the shoulder 23 as will be hereinafter described. In practice the ring 12 may be cylindrical and may be of the same external diameter as the adapter 10. In accordance with the invention the lock ring 12 has keys or lugs 29 projecting from its inner side or interior to cooperate with and move in the grooves 24 and 25 of the mandrel 11. The keys 20 or lugs 29 are proportioned to move freely through the longitudinal grooves 24 and the branch grooves 25. In addition to the keys or lugs 29 the lock ring 11 has one or more fingers or tongues 30 projecting from its lower end. In 25 the typical construction illustrated there are two diametrically opposite tongues 30 spaced from the vertical plane of the keys or lugs 29. The tongues 30 are spaced inwardly from the periphery of the ring 11 and are adapted to fit into or 30 cooperate with the longitudinal grooves 17 in the adapter 10 to releasably connect the adapter and ring 12 against relative rotation while the keys or lugs 29 cooperate with the lower end parts of the longitudinal grooves 24 to connect the ring 35 12 and the mandrel 11 against relative rotation whereby the lock ring 12 forms a connector between the mandrel 11 and the adapter 10 for transmitting rotation in both directions. The lock ring 12 is spring held or spring urged there 40 being a spring 31 for urging the ring 12 downwardly. The spring 31 is a helical compression spring surrounding the mandrel 11 and held under compression between the shoulder 20 and the upper end of the lock ring 12. The upper end 45 of the lock ring 12 may be provided with an upstanding annular flange or ridge 32 to retain the spring 31 in proper cooperation with the ring.

In assembling the setting tool of this invention 50 the lock ring 12 is first arranged on the mandrel 11 from its upper end so that the keys or lugs 29 are received in the longitudinal grooves 24. The spring 31 is then arranged in position on the mandrel 11 and the sub 18 is threaded on the pin or reduced mandrel portion 19 so that the spring 31 is held under compression. The sub 18 may be connected with the lower member of a string of pipe or tubing for running or lowering the liner into the well. The adapter 10 may be 60 readily threaded to a liner, a liner hanger or other tool or piece of equipment to be run into and set or positioned in the well. In the drawings the tubular adapter 10 is shown threaded to a member 13 which will be considered as a 65 liner hanger. To assemble or connect the mandrel 11 and adapter 10 the ring 12 is first moved on the mandrel 11 to bring its keys or lugs 29 into the innermost or closed end portions of the branch grooves 25. This movement of the lock 70 ring 12 on the mandrel 11 brings the tongues 30 of the ring in longitudinal alignment with two of the lugs 26 of the mandrel. Following this initial or preliminary setting of the lock ring 12 the mandrel 11 is introduced or entered in the 75

adapter 10 so that its lugs 26 move into the longitudinal grooves 17. The tongues 30 of the lock ring being behind or aligned with two of the lugs 26 follow the lugs into two of the longitudinal grooves 17 of the adapter 10. The mandrel 11 is moved into the adapter 10 to bring its lugs 26 into the annular groove 16. The mandrel 11 is then turned relative to the adapter 10 to move the lugs 26 into the annular groove 16 and to turn the lugs 29 of the ring 12 into the longitudinal grooves 24 of the mandrel, the tongues 30 of the ring cooperating with the longitudinal grooves 17 of the adapter to hold the ring against turning relative to the adapter whereby the longitudinal grooves 24 of the mandrel are brought into alignment with the lugs 29 simultaneously with the movement of the mandrel lugs 26 in the annular groove 16. The spring 31 acting downwardly on the ring 12 moves the ring downwardly when the lugs 29 and longitudinal grooves 24 are aligned, the downward movement of the ring by the spring bringing the lugs 29 into the lower portions of the longitudinal grooves 24.

The mandrel 11 and the adapter 10 are then locked against relative rotation, the tongues 30 cooperating with the grooves 17 to prevent relative rotation between the adapter 10 and the lock ring 12 and the lugs 29 cooperating with the longitudinal mandrel grooves 24 to lock the mandrel and the ring 12 against relative rotation so that the ring 12 forms a means for connecting the mandrel and adapter against relative rotation. The lugs 26 of the mandrel 11 being located in the groove 16 out of longitudinal alignment with the grooves 17 are adapted to cooperate with the walls of the annular groove 16 to transmit longitudinal forces between the mandrel and adapter.

Following the assembling of the tool and the connecting of the mandrel 11 to the lower member of the string of pipe and the connecting of the adapter 10 to the liner hanger 13, the string may be run into the well to position or locate the liner as desired. The setting tool of the present invention constitutes a positive or dependable connection between the lower end of the string and the liner hanger 13. If the actuation or setting of the liner hanger requires rotary motion then the string may be turned in either direction as required for its operation. The setting tool is adapted to transmit rotation in either direction, the lock ring 12 forming a positive rotation transmitting element between the telescopically assembled adapter 10 and mandrel 11. The openings or passages 28 and 14 of the mandrel and adapter may conduct circulation fluid downwardly from the string to the liner hanger 13 if it is necessary or desirable to flush out the liner. When the liner has been set the mandrel 11 may be easily released from the adapter 10 to permit the removal of the setting string from the well. To release or disconnect the setting tool the string is lowered or allowed to settle causing the mandrel 11 to move downwardly relative to the adapter 10 until its lugs 26 bear on the lower wall of the annular groove 16. This downward movement of the mandrel 11 brings the branch grooves 25 into circumferential or lateral alignment with the lugs 29 of the lock ring 12, the ring being held against downward movement through its engagement with the upper end of the adapter 10. The string may then be given a partial rotation to turn the mandrel 11 to a position where the inner end portions of its branch grooves 25 receive the lugs 29. When

the lugs 29 are in the extreme inner ends of the branch grooves 25 the lugs 26 of the mandrel 11 are in alignment with the longitudinal grooves 17 of the adapter 10. The string may then be raised to move the mandrel upwardly out of the adapter 10 as the lugs 26 may move upwardly through the longitudinal grooves 17 to permit the withdrawal of the mandrel from the adapter. The string carrying the mandrel 11 may then be withdrawn from the well leaving the adapter 10 on the upper end of the liner setter 13.

When it becomes necessary to remove the set liner from the well a string of pipe or tubing carrying the mandrel 11 is run into the well. Prior to the running of the string into the well the lock ring 12 is positioned on the mandrel where its lugs 29 are in the closed or innermost end portions of the branch grooves 25. When the mandrel 11 reaches the tubular adapter 10 its tapered lower surface 27 guides or directs it into the opening 14 of the adapter. When the lock ring 12 is in the position where its lugs 29 are in the innermost portions of the branch grooves 25, the tongues 30 are vertically aligned with two lugs 26. The string is manipulated to cause the lugs 26 of the mandrel to enter the longitudinal grooves 17 of the adapter. The tongues 30 being aligned with the lugs 26 follow the lugs into the longitudinal grooves 17. When the string has been moved downwardly to bring the lugs 26 against the lower wall of the annular groove 16 the mandrel is turned to bring the lugs 29 out of the transverse grooves 25 and into alignment with the vertical grooves 24 which turning simultaneously moves the lugs 26 out of alignment with the grooves 17 to lock the mandrel in the adapter as described above. The setting tool is then locked or assembled to form a positive secure connection between the string and the liner hanger 16 so that the string may be rotated, pulled upwardly or otherwise manipulated to free the liner whereupon the string carrying the liner may be removed from the well.

The form of setting tool illustrated in Figs. 8 to 15, inclusive, of the drawings includes generally, an outer part or adapter 10, a mandrel 40 adapted to fit in the adapter 10 and a lock ring 41 on the mandrel 40 for cooperating with the adapter 10.

The adapter 10 may be identical with the adapter 10 of the previously described form of the invention and the same reference numerals will be employed in referring to its several parts. The adapter 10 may be connected to a liner hanger H, a liner or other part to be positioned or set in a well, and is adapted to remain in the well on the liner hanger or other device when the setting string with the mandrel 40 thereon is removed from the well.

The mandrel 40 is an elongate part adapted to be introduced into the opening 14 of the adapter 10. A threaded pin part 42 is provided on the upper end of the mandrel 40 and is adapted to be threaded into a sub 43 on the lower end of the setting string. The lower portion 44 of the mandrel 40 is of enlarged diameter to fit in or cooperate with the opening 14 of the adapter 10. The mandrel portion 44 is provided with circumferentially spaced lugs 45 adapted to be passed through the longitudinal grooves 17 of the adapter 10 to cooperate with the circumferential groove 16 in the adapter. The lugs 45 may be integral parts of the mandrel 40 and are shaped and proportioned to readily pass through the grooves 17 and to have vertical play or move-

ment in the circumferential groove 16. The mandrel 40 has a central longitudinal fluid passage 39. In accordance with the form of the invention being described the mandrel 40 has 5 projections 46 for cooperating with the lock ring 41. The projections 46 on the mandrel 40 may be in the form of pins threaded into openings in the mandrel or may constitute the end parts of a pin passed through a diametric opening 47 in 10 the mandrel. The projections 46 are spaced some distance above the upper end of the enlarged mandrel portion 44.

The lock ring 41 surrounds and is shiftable on the mandrel 40 between the sub 43 and the upper 15 end of the enlarged mandrel portion 44. The ring 41 is provided with downwardly projecting fingers 48 adapted to extend into the longitudinal grooves 17 of the adapter 10 to lock the ring 41 against turning relative to the adapter. In accordance with the invention the lock ring 41 is provided with substantially U-shaped slots or 20 openings for receiving and cooperating with the projections 46 on the mandrel 40. Each of the openings in the ring 41 has a lower horizontal 25 portion 49 and end ports 50 and 51 extending upwardly from the opposite ends of its horizontal portion 49. These openings in the ring 41 are proportioned to readily receive the projections 46 of the mandrel and may extend through the 30 walls of the ring.

A spring 53 is provided to urge the lock ring 41 downwardly. The spring 53 is in the nature of a helical spring surrounding the mandrel 40 and is arranged under compression between the lower 35 end of the sub 43 and the upper end of the lock ring 41. An annular groove 54 may be provided in the upper end of the lock ring 41 to receive the lower end part of the spring 53.

To assemble the lock ring 41 on the mandrel 40 the lock ring is first passed over the upper end of the mandrel and brought to a position where its openings communicate with the opposite ends of the opening 47. The pin forming the projections 46 is then passed through the opening 47 45 so that its end parts project to form the projections 46 which projections 46 cooperate with the openings in the ring 41. The spring 53 is then arranged on the mandrel 40 and the pin 42 of the mandrel is threaded into the sub 43. 50 This connects the mandrel 40 with the lower end of the setting string. The adapter 10 may be readily connected with or threaded on the liner hanger H, a liner or other piece of equipment to be set in the well. Following the connection of 55 the mandrel 40 with the string and the connection of the adapter 10 with the hanger H the mandrel is releasably connected between the setting string and the hanger or other piece of equipment to be set in the well.

To connect the mandrel 40 with the adapter 10 the ring 41 is first turned and brought to a position where the parts 51 of its openings receive the projections 46. When the ring is in this position its fingers 48 are longitudinally aligned 65 with two of the lugs 45 of the mandrel. The mandrel 40 is then introduced into the adapter 10 so that the lugs 45 enter and move downwardly through the longitudinal grooves 17 of the adapter. The fingers 48 being longitudinally aligned 70 with two of the lugs 45 follow these lugs into two of the adapter grooves 17. The mandrel 40 is then moved downwardly relative to the adapter 10 bringing the ring 41 against the upper end of the adapter 10, and moving the projections 46 75 into the horizontal portions 49 of the ring open-

ings. The spring 53 is compressed during this movement. With the spring 53 held under compression and the projections 46 in the horizontal portions 49 of the ring openings the mandrel and adapter are turned relative to one another to move the projections 46 through the horizontal portions 49 of the ring openings. This relative turning between the mandrel and adapter 10 moves the lugs 45 into the circumferential groove 16 of the adapter so that they are out of alignment with the longitudinal grooves 17. The mandrel 40 and the adapter 10 are turned relative to one another until the projections 46 are in longitudinal alignment with the parts 50 of the ring openings whereupon the adapter 10 and the mandrel 40 are moved longitudinally relative to one another to bring the projections 46 into the upper portions of the opening parts 50. With the parts in this position the lugs 45 are located in the circumferential groove 16 of the adapter at 20 or adjacent its upper wall and out of alignment with the longitudinal grooves 17. The lugs 45 cooperating with the circumferential groove 16 effectively lock the mandrel 40 and the adapter 10 together for the transmission of longitudinal 25 forces and the fingers 48 cooperate with the longitudinal grooves 17 and the projections 46 cooperate with the opening parts 50 to prevent relative turning between the adapter and mandrel. When the parts are in the position just described 30 the setting tool connects the liner hanger H or other device with the setting string so that it may be run into the well on the lower end of the string.

When the hanger H or other device has been 35 run into the well on the string and positioned or set as desired the setting tool may be released to permit the removal of the setting string from the well leaving the hanger H or other device in the well. To release the setting tool the setting 40 string is first moved downwardly moving the lugs 45 into the lower portion of the circumferential groove 16 and moving the projections 46 into circumferential alignment with the horizontal portions 49 of the ring openings. The string is 45 then turned to move the lugs 45 into vertical alignment with the longitudinal grooves 17 of the adapter. This turning movement of the string also moves the projections 46 into vertical alignment with the parts 51 of the ring openings. The 50 fingers 48 cooperating with the longitudinal grooves 17 effectively hold the lock ring 41 against turning during this turning of the string, insuring the proper positioning of the projections 46 when the lugs 45 are brought into vertical alignment with the longitudinal grooves 17. The setting string is then raised. As the lugs 45 are in vertical alignment with the longitudinal grooves 17 they move upwardly through these grooves 55 when the string is raised so that upward movement of the string disengages the mandrel 40 from the adapter 10. Following the release of the mandrel 40 from the adapter 10 the setting string carrying the mandrel 40 may be withdrawn from the well leaving the adapter 10 on the hanger H or other device set in the well.

When it becomes necessary or desirable to remove the liner hanger H or other device with which the adapter 10 is connected the mandrel 40 carrying the lock ring 41 is attached to a suitable string of pipe and is run into the well. Prior to the introduction of the string into the well the lock ring 41 is arranged on the mandrel 40 so that the projections 46 are received in the parts 51 of the ring openings. This longitudinally 75

aligns the ring fingers 48 with the lugs 45 of the mandrel. The string is run into the well until the mandrel enters the adapter 10. The bevelled upper end 15 of the adapter assists in guiding the 5 mandrel into the adapter. It may be found necessary to turn the string to effect the entrance of the lugs 45 into the longitudinal grooves 17 of the adapter. As the ring fingers 48 are vertically aligned with the lugs 45 they follow the lugs 45 10 into the grooves 17. The lock ring 41 may engage the upper end of the adapter 10 to limit the downward movement of the mandrel into the adapter informing the operator of the initial introduction of the mandrel into the adapter. 15 Downward movement of the string is continued to move the projections 46 into the horizontal portions 49 of the ring openings. The string is then turned to move the lugs 45 into the circumferential groove 16 and out of alignment with 20 the longitudinal grooves 17 and to move the projections 46 horizontally in the opening portions 49 to the parts 50 of the openings. The mandrel 40 is then effectively locked in the adapter 10 and the string may be manipulated and raised to 25 withdraw the adapter and the other parts connected with the string from the well.

Having described only typical preferred forms and applications of our invention, we do not wish to be limited or restricted to the specific details 30 herein set forth, but wish to reserve to ourselves any variations or modifications that may appear to those skilled in the art or fall within the scope of the following claims.

Having described our invention, we claim:

35 1. A tool for releasably connecting a string with an object to be set in a well comprising an outer part having an opening, an inner part adapted to be received in the opening, one part being adapted to be connected with the string, the other 40 part being adapted to be connected with the object, disengageable surfaces on the parts adapted to cooperate to transmit longitudinal forces between the parts, and a member shiftably carried by one part and releasably cooperating with the 45 other part to transmit rotation between the parts and to releasably lock the surfaces against disengagement.

2. A tool for releasably connecting a string with an object to be set in a well comprising two parts 50 adapted for telescopic cooperation, a part being adapted to be attached to the string and a part being adapted to be attached to the object, the parts being related for relative longitudinal movement, surfaces on the parts adapted to cooperate 55 to limit relative longitudinal movement between the parts and to transmit longitudinal forces between the parts, the surfaces being releasable by relative turning of the parts, and means locking the parts against relative turning releasable by 60 limited relative longitudinal movement of the parts to allow disengagement of the surfaces, said means including a lock member adapted to have non-rotative engagement with one part while having non-rotative engagement with the other part 65 and freed of said other part to permit relative turning thereof by limited relative longitudinal movement between the parts.

3. A tool for releasably connecting a string with an object to be set in a well comprising two parts 70 adapted for telescopic cooperation, a part being adapted to be attached to the string and a part being adapted to be attached to the object, the parts being related for relative longitudinal movement, surfaces on the parts adapted to cooperate 75 to limit relative longitudinal movement between

the parts and to transmit longitudinal forces between the parts, the surfaces being releasable by relative turning of the parts, and means locking the parts against relative turning releasable by limited relative longitudinal movement of the parts to allow disengagement of the surfaces, said means including a spring urged lock member adapted to have non-rotative engagement with both of the parts and freed from one part to permit relative turning of the parts by limited relative longitudinal movement between the parts.

4. A tool for releasably connecting a well string and an object to be set in a well including two parts, one a tubular member, the other a mandrel adapted to enter the tubular member, one part 15 being connected to the string, the other part being connected to the object, there being a circumferential groove and a longitudinal groove in one part, a lug on the other part normally cooperating with the circumferential groove to prevent separation of the parts and movable in the circumferential groove to allow limited relative longitudinal movement between the parts, and a lock ring 20 cooperating with the parts to prevent relative rotation between the parts and releasable from one part by relative longitudinal movement of the parts to permit the lug to move out through the longitudinal groove whereupon the parts are disengaged.

5. A tool for releasably connecting a well string 30 and an object to be set in a well including two parts, one a tubular member, the other a mandrel adapted to enter the tubular member, one part being connected to the string, the other part being connected to the object, the tubular member having a circumferential groove, and a longitudinal groove joining the circumferential groove, a lug on the mandrel adapted to cooperate with the circumferential groove to prevent separation of the parts, the lug being movable in 40 the circumferential slot to permit limited relative longitudinal movement between the parts, and a shiftable lock ring keyed to the mandrel and normally cooperating with the tubular member to prevent rotation between the parts and freed 45 of keyed engagement with the mandrel by limited relative longitudinal movement of the parts to allow movement of the lug into and through the longitudinal groove.

6. A tool for releasably connecting a well string 50 with an object to be set in a well comprising two parts, one part being connected with the string, the other part being connected with the object, one part being a tubular member having an internal circumferential groove and an internal 55 longitudinal groove joining the circumferential groove, the other part being an inner member to be received in the tubular member, a lug on the inner member adapted to pass through the longitudinal groove when the inner member is introduced in the tubular member and adapted to move into the circumferential groove when the members are turned relative to one another, the lug being adapted to cooperate with the circumferential groove to transmit longitudinal forces 60 between the members and being adapted to move in the circumferential groove to allow limited relative longitudinal movement of the members, and a lock ring on the inner member adapted to cooperate with the tubular member to prevent 65 rotation between the members and thus prevent outward passage of the lug through the longitudinal groove and releasable by limited relative longitudinal movement between the members to permit relative turning between the members 75

which turning brings the lug into the longitudinal groove for movement therefrom when the members are separated longitudinally.

7. A tool for releasably connecting a well string with an object to be set in a well comprising two parts, one part being connected with the string, the other part being connected with the object, one part being a tubular member having an internal circumferential groove and an internal longitudinal groove joining the circumferential groove, the other part being an inner member to be received in the tubular member, the inner member having a longitudinal passage with a lateral branch, a lug on the inner member adapted to move through the longitudinal groove to the circumferential groove when the inner member is inserted in the tubular member and thereafter movable into the circumferential groove by relative turning of the members, the cooperation of the lug and circumferential groove preventing separation of the members, the lug being movable in the circumferential groove to allow limited relative longitudinal movement between the members, a ring movable on the inner member, a tongue on the ring adapted to cooperate with the longitudinal groove to prevent relative turning between the ring and tubular member, and a key on the ring adapted to cooperate with the longitudinal passage to prevent relative turning between the ring and inner member whereby the ring may transmit rotation between the members, the key being aligned with said branch by limited relative longitudinal movement between the members and thereafter being movable into the branch by relative turning between the members to align the lug with the longitudinal groove to permit longitudinal separation of the members.
8. A tool for releasably connecting a well string with an object to be set in a well comprising two parts, one part being connected with the string, the other part being connected with the object, one part being a tubular member having an internal circumferential groove and an internal longitudinal groove joining the circumferential groove, the other part being an inner member to be received in the tubular member, the inner member having a longitudinal passage with a lateral branch, a lug on the inner member adapted to move through the longitudinal groove to the circumferential groove when the inner member is inserted in the tubular member and thereafter movable into the circumferential groove by relative turning of the members, the cooperation of the lug and circumferential groove preventing separation of the members, the lug being movable in the circumferential groove to allow limited relative longitudinal movement between the members, a ring movable on the inner member, a tongue on the ring adapted to cooperate with the longitudinal groove to prevent relative turning between the ring and tubular member, a key on the ring adapted to cooperate with the longitudinal passage to prevent relative turning between the ring and inner member whereby the ring may transmit rotation between the members, the key being aligned with said branch by limited relative longitudinal movement between the members and thereafter being movable into the branch by relative turning between the members to align the lug with the longitudinal groove to permit longitudinal separation of the members, and spring means for yieldingly holding the ring in a position where its key is in the longitudinal passage.
9. A tool for releasably connecting a well string

with an object to be set in a well comprising two parts, one part being connected with the string, the other part being connected with the object, one part being a tubular member having an internal circumferential groove and an internal longitudinal groove joining the circumferential groove, the other part being an inner member to be received in the tubular member, the inner member having a longitudinal passage with a lateral branch, a lug on the inner member adapted to move through the longitudinal groove to the circumferential groove when the inner member is inserted in the tubular member and thereafter movable into the circumferential groove by relative turning of the members, the cooperation of the lug and circumferential groove preventing separation of the members, the lug being movable in the circumferential groove to allow limited relative longitudinal movement between the members, a ring movable on the inner member, a tongue on the ring adapted to cooperate with the longitudinal groove to prevent relative turning between the ring and tubular member, a key on the ring adapted to cooperate with the longitudinal passage to prevent relative turning between the ring and inner member whereby the ring may transmit rotation between the members, the key being aligned with said branch by limited relative longitudinal movement between the members and thereafter being movable into the branch by relative turning between the members to align the lug with the longitudinal groove to permit longitudinal separation of the members, and a spring surrounding the inner member for yieldingly holding the ring in a position where its key is in the longitudinal passage.

10. A tool for releasably connecting a setting string with an object to be set in a well comprising two parts adapted to extend one within the other, one part being adapted to be connected with the string, the other part being adapted to be connected with the object, lugs and grooves on the parts adapted to releasably cooperate to connect the parts for the transmission of longitudinal forces, and means locking the lugs and grooves against disengagement releasable by relative turning between the parts, said means including, a ring having limited turning movement and limited longitudinal movement on one of said parts, and a projection on the ring having non-rotative engagement with the other of said parts and releasable therefrom by longitudinal movement.

11. A tool for releasably connecting a setting string with an object to be set in a well comprising two parts adapted to extend one within the other, one part being adapted to be connected with the string, the other part being adapted to be connected with the object, lugs and grooves on the parts adapted to releasably cooperate to connect the parts for the transmission of longitudinal forces, and means locking the lugs and grooves against disengagement releasable by relative turning between the parts, said means including, a ring shiftable on one of said parts and having an opening, a projection on said part for cooperating with the opening to limit movement of the ring, and a finger on the ring having non-rotative engagement with the other of said parts and releasable therefrom by longitudinal movement between said parts.

12. A tool for releasably connecting a setting string with an object to be set in a well comprising two parts adapted to extend one within the other, one part being adapted to be connected

with the string, the other part being adapted to be connected with the object, lugs and grooves on the parts adapted to cooperate to connect the parts for the transmission of longitudinal movement and releasable by relative turning of the parts, and means for locking the lugs and grooves against disengagement including a ring shiftable on one of said parts and having a substantially

H shaped opening, a projection on said part movable in the opening, and a finger on the ring having non-rotative engagement with the other of said parts and releasable therefrom by longitudinal movement.
